UNITED STATES PATENT OFFICE.

JOHN F. WOLLENSAK, OF CHICAGO, ILLINOIS.

TRAP-LOCK.

SPECIFICATION forming part of Letters Patent No. 369,901, dated September 13, 1887.

Application filed June 28, 1887. Serial No. 242,793. (No model.)

To all whom it may concern:

Be it known that I, JOHN F. WOLLENSAK, a citizen of the United States, residing at Chicago, Illinois, have invented certain new 5 and useful Improvements in Trap-Locks, of which the following is a specification.

The object of my invention is, in general terms, to make a trap-lock that will trap the main key early and twice while the lock is 10 being opened, and which will be difficult to pick; and my invention consists in the features and details of construction hereinafter described and claimed.

In the drawings, Figure 1 is a plan view of 15 my improved lock with the cap or face-plate by which the parts are inclosed removed. Fig. 2 is the same with all the tumblers, except the early-trapping tumbler, removed. Fig. 3 is the same with the main key inserted and the bolt 20 drawn back; and Fig. 4 is the same with the bolt thrown partially forward, the main key trapped, and the racking-stump caught.

In the drawings, A is the lock-case; B, the bolt; C, the spring for holding the bolt out; D, 25 the spring for holding the tumblers down, except when lifted by the key; E, one of the ordinary tumblers; F, the early-trapping tumbler; G, the hook on the same; H, the racking-stump on the bolt-slide; I, the bolt-slide; J, 30 the trap-notch in the ordinary tumbler; K, the trap-notch in the early-trapping tumbler; L, the main key; M, the release-key; N, a cam operated by a thumb-knob on the inside of the lock for pushing the bolt back, and O the 35 racking-stud.

In the use of ordinary trap locks experience 40 has shown two defects, which I will explain and which it is my endeavor to correct in this invention. Where the door does not fit close to the jamb, as is often the case, owing to the shrinkage of the wood, it is possible to open the door without forcing the bolt entirely back. Often by inserting the key and turning back 45 gently, the bolt may be drawn far enough back to enable the door to be opened without being drawn far enough back to trap the key. In such a case a door may be opened and the party remove his key the same as if the lock were an untrapable one. It becomes important, therefore, to effect the trapping of the key at as 50 early a period as possible. The other defect

consists in the fact that after the door has been opened and the key trapped it is possible to pick the lock and remove the key by inserting a bent wire through the hole provided for the release-key. It is therefore important to make some provision for preventing this.

In making my improved lock I provide the usual number of ordinary trapping-tumblers, each provided with a notch, J, as shown in Fig. 1. The main key is provided with a series of wards adapted to engage with each of the ordinary tumblers and lift them up, so as to bring their racking-studs O in the line of the racking-stump H. Just when the racking-studs O have been lifted far enough the key engages with the bolt-slide I, on which the racking-stump H is mounted, and carries it back, together with the bolt, until the racking-stump has passed the racking-studs. When the bolt has been drawn back to this point, the wards of the key enter the notches J in the tumblers E, so that they no longer exert an upward pressure, and the tumblers consequently drop back with their racking-studs in front of the racking-stump, which prevents the bolt from being forced out again by the spring C. At the same time the wards of the key are caught in the notches J, so that it cannot be removed. A release-key, M, must therefore be inserted from the inside to raise the tumblers and release the main key. Thus far I have described generally the parts of an ordinary trap-lock. In addition to these ordinary tumblers I make one or more special tumblers. (Shown in Figs. 2, 3, and 4 as F.) The special tumbler is not provided with the ordinary racking-stud, but has a hook, G, at its forward end. This hook passes down and bends back somewhat, so that its point may rest upon the racking-stump when the bolt is out, as shown in Fig. 2. It is also provided with a trap-notch, K, much closer to its forward end than the ordinary trap-notch, J, as will be seen by an inspection of the notches J and K in Figs. 1 and 2. The notch K in the special tumbler F must be far enough forward to enable the ward to pass into it as soon as or almost as soon as the bolt commences to be drawn back. As will be noticed by looking at Fig. 2, the key can be turned back but a very slight distance until

the hook G drops down in front of the racking-stump, so that the key will be trapped. The bolt has not, however, been as yet moved far enough back to enable the door to be 5 opened, even though quite a space should exist between the edge of the door and the jamb. To draw the bolt back sufficiently to open the door, the key must be turned still farther and the racking - stump drawn back beyond the 10 racking-studs O, when they will fall and trap the key a second time. In this way a double trapping is secured—once almost as soon as the bolt starts back and, secondly, when it has passed back far enough to pass the racking-studs on the ordinary tumblers.

In order to remove the main key, a release-key must be employed or the lock must be picked. If a piece of bent wire or other instrument should be inserted and the ordinary 20 tumblers raised so as to get their racking-studs out of the path of the racking-stump, the spring C would force the bolt forward until it encountered the hook G on the special tumbler F, as shown in Fig. 4. This would bring the 25 wards of the key into the notch K of the special tumbler, and this tumbler would have to be lifted before the key could be turned farther forward and released; but the hook G is provided with a slight backward turn, which 30 would prevent this tumbler being raised. If in this dilemma the party should turn his key in the other direction, he would simply trap it again in the ordinary tumblers, and when he had succeeded in raising these tumblers the 35 spring C would carry the bolt forward and the racking-stump with it into contact with the hook G again. This operation could be continued indefinitely without being able to remove the main key; nor would the situation 40 be improved by raising with the bent wire the special tumbler first, because there would be nothing to hold such special tumbler up, and

the moment the bent wire was used to raise the ordinary tumblers so that the bolt could advance the special tumbler would fall into 45 position again to catch the racking-stump in the hook G. In this way picking the lock shut, so to speak, after it had been opened by the main key would be practically impossible.

It will be seen that the gist of my invention 50 consists in the employment of one or more tumblers trapable at one point and one or more tumblers trapable at another point as the main key draws the bolt back, so that the key will be early and twice trapped, and the 55 employment of a hook on one of the tumblers whose inner surface, against which the racking-stump contacts, is in advance of the inner surfaces of the racking - studs on the other tumblers. Under these circumstances I do 60 not care to limit myself to all the specific details of construction described and shown, as my invention consists more in the employment of tumblers embodying the ideas above specified than in the shape and form of the parts 65 by which these ideas are effectuated.

What I regard as new, and desire to secure by Letters Patent, is—

1. In a lock, a tumbler provided with a trapping - notch, K, and a tumbler provided 70 with a trapping-notch, J, into which notches the wards of the main key successively pass and are trapped at different points in moving the bolt back, substantially as described.
2. In a lock, the combination of a tumbler 75 provided with a racking-stud, a tumbler provided with a hook the inner surface of which is in advance of the inner surface of the racking-stud, and a bolt-slide provided with a racking-stump, substantially as described.

JOHN F. WOLLENSAK.
